ATTORNEY.

UNITED STATES PATENT OFFICE.

MILTON A. FESLER, OF SAN FRANCISCO, CALIFORNIA.

OIL-BURNER.

1,026,664.

Specification of Letters Patent.

Patented May 21, 1912.

Application filed July 27, 1908, Serial No. 445,496. Renewed July 12, 1910. Serial No. 571,657.

To all whom it may concern:

Be it known that I, MILTON A. FESLER, a citizen of the United States, residing at San Francisco, in the county of San Francisco and State of California, have invented new and useful Improvements in Oil-Burners, of which the following is a specification.

The object of the present invention is to provide an improved oil burner.

10 In the accompanying drawing, Figure 1 is a broken side view of the oil burner; Fig. 2 is a sectional view of a furnace showing the oil burner in position.

Referring to the drawing, 1 indicates a 15 furnace, supported upon a suitable base 2, upon which rests, at the center of the furnace, a standard 3 from which project laterally upper and lower bearings 4, 5. Supported upon said bearings are bushings 6, 20 in which rotates a vertical tube 7, upon which is secured a pulley 8 driven by a belt 9 from any suitable source of power. The specific means for rotating the tube is immaterial to the present invention. Through 25 said tube extends centrally a stationary oil supply pipe 10 to the top of which is secured a conical spreader 21. The oil passing through said pipe 10 flows down said spreader on to the upper flat surface of a 30 deflector wheel 11 having a hub 12 secured to the tube and having also an outer rim 13. The top of said wheel is closed by a cap 14 and to said rim are secured a number, as four, of tapering tubes 15. By the 35 rapid rotary motion imparted to the tube 7 and therefore to the wheel, the oil is forced against the inner surface of the rim 13 and down oil conduits 16, one leading into each tube 15.

40 Surrounding the burner proper are upper and lower concave partitions 17, 18, the lower partition 18 being formed near the outer edge with openings 19 for admitting air into the narrow space between the partitions. In this space the air becomes highly 45 heated by reason of the high temperature of the upper partition 17, and the heated air passes upward between the hub 12 and the rim 13 of the wheel. Hence it passes into 50 the tubes 15 by means of holes 23 in said rim registering with the inner ends of said tubes. It is by reason of the rapid rotary motion of these tubes that the air is drawn through the openings 19 in the lower partition 55 into the space between the two partitions. The oil and air are then thrown out-

ward with great velocity, and on account of this velocity the oil is very finely atomized and commingled with the hot air. It is thus burned in a very effective manner. 60

I find that for the successful operation of this burner the air and vaporized oil issuing from the rotating conduits must have a clear flight of a length not less than the length of the conduits, before impinging 65 upon a wall or any other obstruction, otherwise the oil will carbonize and deposit carbon upon the obstructing wall.

I claim:

1. In an oil burner, the combination of 70 bearings, a vertical tubular shaft in said bearings, means for rotating said shaft in said bearings, a deflector wheel secured at the upper end of said shaft and having a depending outer rim spaced from said shaft, 75 and outwardly extending tubes secured to said rim and communicating with the space between said rim and shaft, said wheel having oil conduits leading into the respective tubes, substantially as described. 80

2. In an oil burner, the combination of 85 bearings, a vertical tubular shaft in said bearings, means for rotating said shaft in said bearings, a deflector wheel secured at the upper end of said shaft and having a depending outer rim spaced from said shaft, a cap inclosing the top of the wheel and forming therewith an oil chamber, and outwardly extending tubes secured to said rim and communicating with the space between 90 said rim and shaft, said wheel having oil conduits leading into the respective tubes, substantially as described.

3. In an oil burner, the combination of 95 bearings, a vertical tubular shaft in said bearings, means for rotating said shaft in said bearings, a deflector wheel secured at the upper end of said shaft, an oil tube leading centrally through said hollow shaft, and a conical spreader secured to the top of said 100 oil tube and discharging on to said wheel, substantially as described.

4. In a furnace, the combination of upper 105 and lower partitions therein, a centrifugal oil burner above the upper partition, and means for admitting air into the space between the partitions at points remote from said oil burner, substantially as described.

5. In a furnace, the combination of upper 110 and lower concave partitions, a stand below said partitions, bearings supported by said stand, a vertical tube rotatably supported in

2

said bearings, an oil supply pipe passing through said tube, a deflector secured upon the upper end of the tube, deflector tubes extending from said deflector, means carried by the upper end of said oil supply pipe for supplying oil to said deflector, and means for rotating said tube, substantially as described.

6. In an oil burner, the combination of a vertical shaft, means for rotating said shaft, a deflector secured upon the upper portion of said shaft, and having a ring spaced from the shaft, said deflector having air conduits leading outwardly from the space between said ring and shaft, and means for supplying oil to said conduits, substantially as described.

7. In an oil burner, the combination of a vertical shaft, means for rotating said shaft, air conduits rotated with said shaft, arranged to receive air at the inner end thereof, and means for conveying oil into the

inner ends of said conduits, substantially as described.

8. The combination of a furnace, an oil burner therein, having conduits for the air and oil of combustion, and means for rotating said conduits, the conduits being more remote from the wall of the furnace than the length of said conduits, substantially as described.

9. In an oil burner, the combination of a rotatable vertical shaft, a deflector therefor comprising a cap and air conduits both rotating with said shaft, and an oil pipe discharging into said deflector beneath said cap, substantially as described.

In testimony whereof I have hereunto set my hand in the presence of two subscribing witnesses.

MILTON A. FESLER.
